[57] ABSTRACT

A tone control circuit, wherein variable resistors for controlling low-, middle- and high-frequency tones are each connected at one end to the input terminal of said control circuit and at the other end to the output terminal of said control circuit to which the output terminal of an amplifier is connected; the sliding member of the low-frequency tone-controlling variable resistor is connected to the input terminal of the amplifier through a resistor and also to the output terminal of said amplifier through a resistor, capacitor and resistor in turn and further to the input terminal of the control circuit through the resistor and capacitor; the sliding member of the middle-frequency tone-controlling variable resistor is connected to the input terminal of the amplifier through a capacitor and resistor; and the sliding member of the high-frequency tone-controlling variable resistor is connected to the input terminal of the amplifier through a capacitor.

3 Claims, 4 Drawing Figures

FIG. 2
PRIOR ART

TONE CONTROL CIRCUIT

BACKGROUND OF THE INVENTION

This invention relates to a tone control circuit, and more particularly to a tone control circuit so improved as to prevent high-frequency tones from being affected when middle-frequency tones are controlled.

With the prior art tone control circuit, the variable resistors VR_1 , VR_2 , VR_3 for controlling low-, middle- and high-frequency tones are each connected, as shown in FIG. 1, at one end to the input terminal t_i of said circuit through resistors R_1 , R_3 , R_5 respectively and at the other end to the output terminal t_o of said circuit through resistors R_2 , R_4 , R_6 . Both ends of the variable resistor VR_1 are connected to the corresponding sliding member through capacitors C_2 , C_3 respectively. Said sliding member is connected to the input terminal of the amplifier AMP through a resistor R_7 . A capacitor C_1 is connected between both ends of the variable resistor VR_2 . The sliding members of the variable resistors VR_2 , VR_3 are connected to one end of a capacitor C_5 through the corresponding resistor R_8 and capacitor C_4 . The other end of said capacitor C_5 is connected to the input terminal of the amplifier AMP.

With the prior art tone control circuit of FIG. 1, the capacitors C_1 , C_4 have a very small reactance relative to the high frequency, and is regarded as forming the circuit of FIG. 2 with respect to said frequency. Referring to FIG. 2, when the sliding member of the variable resistor VR_3 is positioned at point *a*, the greater part of input current is supplied to the amplifier AMP through the resistor R_8 and capacitor C_4 , and most of the feedback current is brought back to said amplifier AMP through the resistor R_4 , variable resistor VR_2 and resistor R_8 in turn. When, therefore, the capacitor C_4 decreases in reactance with an increase in frequency, a larger amount of input current is introduced, whereas the feedback current is maintained at a prescribed amount, thus causing the tone control circuit to raise the high frequency tones. Where, under this condition, the sliding member of the middle-frequency tone controlling variable resistor VR_2 is shifted, the feedback current varies in amount, thus changing the high-frequency tones. When the sliding member of the high-frequency tone-controlling variable resistor VR_3 is brought to point *b*, then most of the input current is delivered to the amplifier AMP through the resistor R_3 , variable resistor VR_2 and resistor R_8 in turn, while the feedback current is returned to the amplifier AMP through the resistor R_6 and capacitor C_4 . With the prior art tone control circuit, therefore, the raised frequency only leads to an increase in the amount of feedback current, causing the tone control circuit eventually to decrease the high-frequency. In this case, too, the movement of the sliding member of the variable resistor VR_2 varies the high-frequency tones.

As apparent from the foregoing description, the prior art tone control circuit has the drawback that the varied resistance of the middle-frequency tone-controlling variable resistor VR_2 changes the high-frequency tones.

SUMMARY OF THE INVENTION

It is accordingly the object of this invention to provide a tone control circuit wherein the middle-frequency tone-controlling resistor can be operated without changing the high-frequency tone.

According to an aspect of this invention, there is provided a tone control circuit, wherein variable resistors for controlling low-, middle- and high-frequency tones are each connected at one end to the input terminal of said control circuit and at the other end to the output terminal of said control circuit. The sliding member of a low-frequency tone-controlling variable resistor is connected to the input terminal of an amplifier through a first resistor and also to a second resistor, which in turn is connected to first and second capacitors connected to both terminals of a middle-frequency tone-controlling variable resistor. The sliding member of the middle-frequency tone-controlling variable resistor is connected to the input terminal of the amplifier through a third resistor. The sliding member of a high-frequency tone-controlling variable resistor is connected to the input terminal of the amplifier through a third capacitor.

BRIEF DESCRIPTION OF THE DRAWING

FIG. 1 is a diagram of the prior art tone control circuit;

FIG. 2 is an equivalent circuit diagram of FIG. 1 relative to high frequency;

FIG. 3 is a diagram of a tone control circuit according to an embodiment of this invention; and

FIG. 4 is a diagram of a tone control circuit according to another embodiment of the invention.

DETAILED DESCRIPTION OF THE INVENTION

Referring to the first embodiment of FIG. 3, a low-frequency tone-controlling variable resistor VR_{11} is connected at one end to the input terminal t_i of said control circuit through a resistor R_{11} and at the other end to the output terminal t_o of said control circuit through a resistor R_{12} . A middle-frequency tone-controlling variable resistor VR_{12} is connected at one end to the input terminal t_i of said control circuit through a resistor R_{13} and at the other end to the output terminal of said control circuit through a resistor R_{14} . A high-frequency tone-controlling variable resistor VR_{13} is connected at one end to the input terminal t_i of said control circuit through a resistor R_{15} and at the other end to the output terminal t_o of said control circuit through a resistor R_{16} . One terminal of the variable resistor VR_{11} is connected to the corresponding terminal of the variable resistor VR_{12} through series connected capacitors C_{11} , C_{12} and the opposite terminal of said variable resistor VR_{11} is connected to the corresponding terminal of said variable resistor VR_{12} through series connected capacitors C_{13} , C_{14} . A line connecting the junction of the capacitors C_{11} , C_{12} and that of the capacitors C_{13} , C_{14} is connected to the sliding member of the variable resistor VR_{11} through a resistor R_{17} . Said sliding member is connected to the input terminal of the amplifier AMP through a resistor R_{18} . The sliding member of the variable resistor VR_{12} is connected to the input terminal of the amplifier AMP through series connected capacitor C_{15} and resistor R_{19} . The sliding member of the variable resistor VR_{13} is connected to the input terminal of the amplifier AMP through a capacitor C_{16} . The output terminal of said amplifier AMP is connected to the output terminal t_o of the control circuit.

There will now be described the operation of the tone control circuit arranged as described above according to the embodiment of FIG. 3. The capacitors C_{11} , C_{12} ,

C_{13} , C_{14} , C_{15} are chosen to have such a capacity as makes their reactance very small relative to the high-frequency. When, therefore, the sliding member of the high-frequency tone-controlling variable resistor VR_{13} is positioned at point a, then most of the input current having the high frequency is supplied to the input terminal of the amplifier AMP through the resistor R_{15} and capacitor C_{16} . The greater part of current initially delivered from the amplifier AMP is fed back thereto through the resistor R_{14} , capacitor C_{14} , resistor R_{17} and resistor R_{18} in turn. In this case, a very small amount of current is fed back to the amplifier AMP through the resistor R_{14} , variable resistor VR_{12} , capacitor C_{15} and resistor R_{18} in turn. Accordingly, the shifting of the sliding member of the variable resistor VR_{12} gives rise to little change in the amount of feedback current, substantially saving the increasing characteristics of the high-frequency tone from the effect of the operation of the middle frequency tone-controlling variable resistor VR_{12} .

When the sliding member of the high-frequency tone-controlling variable resistor VR_{13} is brought to point b, most of the input current having the high frequency is supplied to the amplifier AMP through the resistor R_{13} , capacitor C_{12} and resistors R_{17} , R_{18} in turn. The greater part of current initially delivered from the amplifier AMP is fed back thereto through the resistor R_{16} and capacitor C_{16} . Therefore, only a very small amount of current passes through the variable resistor VR_{12} , capacitor C_{15} and resistor R_{19} in turn, giving rise to little change in the input current even when the sliding member of said variable resistor VR_{12} is shifted. As the result, the operation of the middle-frequency tone-controlling variable resistor VR_{12} little affects the decreasing characteristics of the high-frequency tone.

As apparent from the foregoing description, the tone control circuit of this invention substantially prevents the high-frequency tone from being disturbed by the operation of the middle-frequency tone-controlling variable resistor VR_{12} . Accordingly, where the high-frequency tone-controlling resistor is adjusted to have desired increasing and decreasing characteristics of the high-frequency tones and then the middle-frequency tone-controlling resistor is adjusted, the necessity of controlling the high tone frequency for a second time is eliminated since the high-frequency tone characteristics are little affected due to the adjusting operation of the middle-frequency tone-controlling resistor.

There will now be described the operation of a tone control circuit according to the second embodiment of FIG. 4. When the sliding member of the high-frequency tone-controlling variable resistor VR_{13} is positioned at point a, the greater part of current initially delivered from the amplifier AMP is fed back thereto through the resistor R_{14} , capacitor C_{18} , capacitor C_{20} , and resistors R_{17} , R_{18} in turn. When the sliding member of the high-frequency tone-controlling variable resistor VR_{13} is brought to point b, then most of the input current is delivered to the amplifier AMP through the resistor R_{13} , capacitors C_{17} , C_{19} and resistors R_{17} , R_{18} in turn. The greater part of current initially supplied by the amplifier AMP is fed back thereto through the resistor R_{16} and capacitor C_{16} . The second embodiment of the above-mentioned circuit arrangement attains the same effect as the first embodiment.

As mentioned above, the tone control circuit of this invention has such an arrangement as substantially pre-

vents the input current and feedback current reproducing high-frequency tones from being conducted through the middle-frequency tone-controlling variable resistor, thereby little changing the high-frequency tones when the middle-frequency tone-controlling resistor is controlled.

What is claimed is:

1. A tone control circuit, wherein low-, middle- and high-frequency tone-controlling variable resistors are each connected at one end to the input terminal of said control circuit and at the other end to the output terminal of said control circuit; the low-frequency tone-controlling variable resistor has a sliding member which is connected through a first resistor to the input terminal of an amplifier whose output terminal is connected to the output terminal of said control circuit and which sliding member is also connected to one terminal of a second resistor, the opposite terminal of which is connected to both terminals of the middle-frequency tone-controlling variable resistor through first and second capacitors respectively; the sliding member of said middle-frequency tone-controlling variable resistor is connected to the input terminal of the amplifier through a third capacitor and a third resistor; and the sliding member of the high-frequency tone-controlling variable resistor is connected to the input terminal of the amplifier through a fourth capacitor.

2. A tone control circuit, wherein low-, middle- and high-frequency tone-controlling variable resistors are each connected at one end to the input terminal of said control circuit and at the other end to the output terminal of said control circuit; the low-frequency tone-controlling variable resistor has a sliding member which is connected through a first resistor to the input terminal of an amplifier whose output terminal is connected to the output terminal of said control circuit and which sliding member is also connected to one terminal of a second resistor, the opposite terminal of which is connected to both terminals of the low-frequency tone-controlling variable resistor through first and second capacitors respectively and also to both terminals of the middle-frequency tone-controlling variable resistor through third and fourth capacitors respectively; the sliding member of the middle-frequency tone-controlling variable resistor is connected to the input terminal of the amplifier through a fifth capacitor and a third resistor; and the sliding member of the high-frequency tone-controlling variable resistor is connected to the input terminal of the amplifier through a sixth capacitor.

3. A tone control circuit, wherein low-, middle- and high-frequency tone-controlling variable resistors are each connected at one end to the input terminal of said control circuit and at the other end to the output terminal of said control circuit; the low-frequency tone-controlling variable resistor has a sliding member which is connected through a first resistor to the input terminal of an amplifier whose output terminal is connected to the output terminal of said control circuit, and which sliding member is also connected to one terminal of a second resistor, the opposite terminal of which is connected to both terminals of the low-frequency tone-controlling variable resistor through first and second capacitors respectively; the middle-frequency tone-controlling variable resistor is connected at one end to the opposite terminal of the second resistor through a third capacitor and said first ca-

pacitor, and at the other end to said opposite terminal of the second resistor through a fourth capacitor and said second capacitor and is provided with a sliding member which is connected to the input terminal of the amplifier through a fifth capacitor and a third resistor; 5

and the high-frequency tone-controlling variable resistor has a sliding member which is connected to the input terminal of the amplifier through a sixth capacitor.
